FILTER FOR AN OXYGENATION SYSTEM

David J. Rosenberg, Glen Cove, N.Y., assignor to
Pall Corporation, Glen Cove, N.Y.

Filed June 16, 1972, Ser. No. 263,497

Term of patent 14 years

Int. Cl. D24—02

U.S. Cl. D83—1 R

FIG. 1

FIG. 2

FIG. 1 is a top plan view of a filter for an oxygenation system showing my new design, the bottom being the same as the top shown; and

FIG. 2 is a side elevational view thereof.

I claim:

The ornamental design for a filter for an oxygenation system, substantially as shown and described.
